CONTAINER BODY FORMING MECHANISM

John M. Hothersall, Brooklyn, N. Y., assignor to
American Can Company, New York, N. Y., a
corporation of New Jersey

Original application June 20, 1933, Serial No.
676,749, now Patent No. 2,056,192, October 6,
1936. Divided and this application September
24, 1935, Serial No. 41,949

6 Claims. (CL. 153—9)

The present invention relates to apparatus for making sheet metal container bodies such as are used for holding paint, white lead and other heavy products and has particular reference to mechanism for shaping the body wall to produce beaded, necked-in, and the like sections in the body while at the same time avoiding the setting up of uneven stresses in the body wall during the shaping operation. This is a division of my 5 U. S. application Serial Number 676,749, filed June 20, 1933, (Patent No. 2,056,192 granted October 6, 1936), on Art of making container bodies.

An object of the present invention is the provision of a mechanism for shaping preformed tubular container bodies wherein the shaping is done in a simple and effective manner as by a combination beading, rolling and spinning action on the body wall without distortion or uncontrolled bending of the body material. This control during bending or beading is particularly desirable in the manufacture of larger sizes of containers which are necessarily of relatively heavy gauge metal but the instant invention is also of benefit in the manufacture of containers of other sizes and of metal of other gauges. 20

Another object is the provision of such a mechanism for container bodies in which the container body side walls is progressively beaded and rolled to produce the desired section in which only a small area of the material at a given time is undergoing a change in shape. 25

The invention also provides for flanging both ends of the tubular body in the same mechanism that produces the shaping operations, thus simplifying this part of the body manufacture. 30

The mechanism herein disclosed as a form found preferable up to the present time is believed to be novel in utilizing a new kind of beading operation on the body walls of tubular bodies by progressively and laterally engaging the wall sections and moving along the body thereby introducing a spinning action in addition to beading. 40

Numerous other objects and advantages of the invention will be apparent as it is better understood from the following description, which, taken in connection with the accompanying drawing, discloses a preferred embodiment thereof. 45

Referring to the drawing:

50 Figure 1 is a perspective view of a tubular container body prior to being subjected to further shaping operations by mechanism embodying the present invention;

55 Fig. 2 is a perspective view of the container

body after shaping and also showing the ends of the body flanged;

Fig. 3 is a longitudinal sectional view of body flanging and shaping elements of a mechanism embodying the instant invention, the view showing the elements in position at the completion of the flanging operation and at an intermediate step of the body shaping operation; and 5

Fig. 4 is a view similar to Fig. 3 showing the shaping elements in the final shaping position. 10

As a preferred embodiment of the invention the drawing illustrates a mechanism which is adapted to flange the ends of preformed tubular container bodies *a* (Fig. 1) and to shape the side walls of the bodies so that each body includes 15 an elongated inwardly pressed bead *b* (Fig. 2).

These bodies may be of single body length in which the bead may be formed in any desirable part of the body depending upon the use to be made of the bead or they may be of double body 20 length having the bead so positioned that it will be incorporated entirely in one of the bodies or so that there will be a part in each of them after the original double body is cut in two in a subsequent operation. This latter form of body obtained from the double body length is well 25 adapted to the manufacture of paint pails, lead kegs, and the like where it is desirable to have the upper end of the body reduced in diameter or necked-in, the bead forming this necked-in 30 part of the body.

The mechanism for shaping or perhaps more accurately reshaping the container bodies of one type comprises in part a pair of flanging and beading heads *12* (Figs. 3 and 4) on which a body 35 *a* is placed. These heads are of identical construction and are inserted into the open ends of the body. Each head *12* is carried upon or may be a part of a horizontal shaft *13* which is suitably mounted for rotation on its own axis and 40 also for longitudinal movement. It is the longitudinal movement of the heads that effect their insertion into the ends of the body.

Each head *12* is formed with a flanging ridge 45 *14* in which an annular groove *15* is disposed. The heads *12* in coming into the body *a* move into the position illustrated in Figs. 3 and 4 and in reaching this position the two outer edges of the body are caused to pass into the flanging grooves *15* and are deflected outwardly as they follow the 50 walls of the grooves. Flanges *c* (see also Fig. 2) are thus formed at each end of the tubular body.

Each head *12* is reduced in diameter at its inner end and is formed with a stem *17*. A backing-up ring *18* is slidably mounted upon each stem 55

17 and is held on the stem by a clamping nut 19 which is threaded onto the end of the stem. Springs 22 are interposed between each head 12 and its backing-up ring 18 and these normally 5 hold the latter against its nut 19. Each ring 18 is prevented from rotating on its stem 17 by a feather 23 which, however, allows for longitudinal sliding movement.

The inner corner of each backing-up ring 18 is 10 cut away and is formed with a concave annular grooved surface 26. The two concave surfaces 26 of the adjacent rings, when the heads 12 are inserted in the body, together provide a semi-circular groove which is used in the next or beading operation now to be described.

The beading is effected by two beading rollers 31 which are pinned to the inner ends of a pair of axially aligned shafts 32. These shafts are parallel to the shafts 13 of the flanging and beading heads and are suitably mounted so that they may be simultaneously moved inwardly toward the shafts 13 while still maintaining parallelism. For the first step in the beading operation the ends of the two shafts 32 are disposed in close proximity, their rollers 31 then being close together but not touching, as shown in Fig. 3.

Each roller 31 is formed with a rounded ridge or projection 33 and these cooperate, when the rollers are in the position illustrated in Fig. 3, 30 to present a semi-circular peripheral ridge corresponding in contour to the semi-circular groove of the two cooperating rings 18.

To effect the beading operation the shaft 32 are moved inwardly as a unit toward the shafts 13 and 35 the rounded projections 33 of the beading rollers press against and reshape the tubular body *a*. It will be understood that the body is rapidly turning with the rotating heads 12 and the rollers 31 are correspondingly rotated. The material of 40 the body which is engaged by the rollers is thus gradually and progressively forced inwardly against the concave walls 26 of the backing-up rings 18. An annular bead *d* is thus formed in the body wall, Fig. 3 illustrating the completion 45 of this part of the beading operation.

The bead *d* is used as a starting shape in the forming of the desired elongated bead portion of the container body. As a further step this bead is widened by a continuation of the rolling action plus a separation of the beading rollers 31 as 50 their shafts 32 are drawn apart along their aligned axes. The rotating shafts 32 at such time are still maintained in parallelism with and at the same distance from the rotating head shafts 55 13. -

During this separation of the shafts and the beading rollers the projecting ridges 33 of the rollers, pressing through the confined wall of the tubular body *a*, force apart the backing-up rings 60 18 moving them outwardly on their stems 17 against the action of the springs 22. These movements widen the narrow bead *d* into the elongated bead *b* (as shown in Figs. 2 and 4).

The body *a* during this beading action is confined between the flanging projections 14 of the heads 12 and the material of the wall is gradually pressed inwardly in a combined beading and spinning action which is much easier on the body, avoiding any sudden or intense strains which would necessarily be present in straight die action. In 70 the case of a double length body, it is this beaded section *b* which provides the necked-in parts of the container when the body is subsequently cut in two.

75 The beading roller shafts 32 are now moved

back and away from the body on the flanging and beading heads 12 and the latter are then withdrawn from the body. In this withdrawing action the springs 22 pressing their associated backing-up rings 18 against the walls of the bead *b* assist in knocking off or disengaging the beaded body from the beading heads.

It should be understood that a single beading roller could also be made if desired to produce the elongated beaded section *b*, such a roller having a 10 shaped contour adapted to form the starting bead *d* and upon movement of the roller longitudinally of the body to expand or shape the bead *d* into the elongated bead *b*.

Although the drawing illustrates a mechanism 15 adapted to form an inwardly disposed bead in the container body by reducing the diameter of the latter it should be understood that an external or outwardly disposed bead provided by expanding the body diameter can also be made 20 by transposing the beading elements so that backing-up elements 18 will be on the outside of the body and the beading rollers 31 will be disposed inside the heads 12.

It is thought that the invention and many of 25 its attendant advantages will be understood from the foregoing description, and it will be apparent that various changes may be made in the form, construction and arrangement of the parts without departing from the spirit and scope of 30 the invention or sacrificing all of its material advantages, the form hereinbefore described being merely a preferred embodiment thereof.

I claim:

1. An apparatus for making necked-in container bodies which comprises, the combination of a pair of rotatable beading heads for supporting a tubular body, beading rollers for forming a grooved bead in said body while it is being rotated by said heads, and means for moving said 35 rollers first into the body wall at its center and thence away from each other and, while in operation endwise and parallel to the axis of rotation to widen said grooved bead and form a necked-in section in the middle of said tubular 40 body. 45

2. An apparatus for making beaded container bodies which comprises, the combination of rotatable beading heads adapted for cooperative longitudinal and opposite movement into the open 50 ends of a tubular body for supporting the same in beading position, a pair of cooperating beading rollers for forming a grooved bead in said body while it is being rotated by said heads, and means for moving said rollers first as a unit into 55 the body wall at right angles to its axis of rotation and thence away from each other with an endwise movement parallel to the said axis of rotation to widen said grooved bead and form a beaded section for said tubular body. 60

3. An apparatus for making container bodies which comprises, the combination of rotatable beading heads adapted for longitudinal movement into the open ends of a tubular body for supporting the body in beading position, a pair of cooperating beading rollers for forming a grooved bead in said body while it is being rotated by said heads, backing-up means carried by 65 said heads for backing-up the inside wall of said body during the beading operation, and means 70 for moving said rollers first as a unit into the body wall of said tubular body and shaping it against said backing-up means to form a simple bead and thence outwardly with an endwise movement parallel to the axis of rotation to widen 75

said simple bead into an elongated bead, said backing-up means being movable relative to said heads and separating and moving with said beading rollers to effect a continued backing-up of said body wall during its reshaping to form a section for said tubular body.

4. An apparatus for making necked-in container bodies which comprises, the combination of rotatable beading heads for supporting a tubular body in beading position, a pair of co-operating beading rollers for forming a grooved bead in said body while it is being rotated by said heads, and backing-up rings carried inside of said heads and having longitudinal movement therewith for backing-up the inside wall of said body during the beading operation, said beading rollers moving first as a unit into the body wall of said tubular body and shaping it against said backing-up means and means for moving said rollers oppositely with an endwise movement parallel to the axis of rotation to widen said grooved bead, said backing-up rings being movable longitudinally of said heads and backing-up said body wall during the separation of said beading rollers to form a necked-in section for said tubular body.

5. An apparatus for making container bodies which comprises, the combination of a rotatable beading head for supporting a tubular body, oppositely movable beading rollers for forming a grooved bead in said body while it is being rotated by said heads, and backing-up means movable on said head, and means for moving said roller first into engagement with the body wall and thence endwise and parallel to its axis of rotation to widen said grooved bead and form a shaped section for said tubular body, and means for flanging the ends of said body.

6. An apparatus for making necked-in container bodies having in combination rotatable and oppositely movable heads for entering and supporting a cylindrical sheet metal body, backing-up rings mounted to slide in said heads, springs for pressing said rings inwardly and oppositely, and beading rollers movable inwardly against said body and movable oppositely and longitudinally to neck-in the median portion of the body while moving said rings.

JOHN M. HOTHERSALL. 25
